D. 353,897 12/1994 Cole D25/124

Primary Examiner—Doris Clark

[57] **CLAIM**

The ornamental design for a casement frame, as shown and described.

DESCRIPTION

FIG. 1 is a perspective view from above the casement frame; and,

FIG. 2 is an end view of the casement frame.

The casement frame is broken away in the center to indicate indeterminate length.
